FURNITURE

Albert Ernest and Isador Waldman, Chicago, Ill.

Application March 20, 1936, Serial No. 69,862

6 Claims. (Cl. 155—53)

This invention relates to furniture, chairs and the like, and more particularly to the type commonly known as easy chairs which are generally provided with upholstering over the supporting surfaces. It is an object of this invention to provide a chair having a full floating seat portion with resilient support not only for vertical displacement but also for horizontal displacement.

It is a further object to provide a chair having a resilient support for the legs of a person, which is generally known in the trade as a spring edge.

An additional object is to provide a chair wherein the resilient seat portion may be added or removed as a unit therefrom, facilitating repair and replacement. Further objects are to provide an easy chair of the sanitary type having a removable seat cushion and wherein ready access to the resilient seat assembly is possible. An additional object is to provide a comfortable easy chair, of simple and cheap mechanical construction providing a full floating seat from which anyone may rise without the usual difficulty.

Further objects are to provide a construction of maximum simplicity, economy and ease of assembly, and such further objects, advantages and capabilities as will later more fully appear and as are inherently possessed thereby.

The invention further resides in the combination, construction, and arrangement of parts illustrated in the accompanying single sheet of drawings, and while there is shown therein a preferred embodiment, it is to be understood that the same is capable of modification and change and comprehends other details and constructions without departing from the spirit of the invention.

Referring to the drawing:

Figure 1 is a perspective view of a chair embodying this invention with upholstery removed. Figure 2 is a fragmentary side view in perspective of the chair of Figure 1.

Figure 3 is a fragmentary top plan view in perspective of a chair with upholstery applied but without the removable seat cushion.

The chair comprises four bottom rail members 1-4 inclusive forming a rectangular frame supported at the corners by four legs of which 5, 6 and 8 only are visible. Front legs 5 and 8 extend upwardly above the frame to form posts 9 and 10 upon which arm rests 11 and 12 are supported. Rear leg 6 extends upwardly to form a frame member 15 while a similar member 16 extends from the fourth leg. Arm rests 11 and 12 are suitably fastened at their ends to members 15 and 16. The top free ends of members 15 and

16 are joined by a top member 18 of any suitable design. An inner frame for the back cushion is formed by vertical members 19 and 20 joined at the top to member 18 and at the bottom to a cross member 21 rigidly positioned between back frame members 15 and 16.

It is understood of course that the various members are suitably shaped and finished to make a comfortable easy chair frame, with the back frame bending away.

A side member or middle rail 26 extends from cross member 21 to post 10 while a similarly positioned member or middle rail 27 extends from member 21 to post 9. These members, 26 and 27, are at seat level and function as top stops for a resiliently mounted seat assembly.

The seat assembly consists of a heavy wire frame 28, preferably steel wire, shaped to form a rectangular seat with four sides 29-32 inclusive. Transverse sides 29 and 31 preferably extend beyond stop members 26 and 27 and are bent upwardly to form eyes 33-36 inclusive. From each eye helical tension springs 37 extend upwardly to engage the lower part of arm rests 11 and 12 at the front and rear respectively. From rear side 31 of the seat frame, coil springs 38 extend to metal anchors 39 on rear bottom frame member 3 adjacent the ends thereof. It will be noted that springs 38 extend downwardly and rearwardly providing both vertical and horizontal components of resiliency. It is to be stated that the same effect, resiliency and stability, can be obtained by eliminating the helical tension springs 37 and using instead two rearward helical tension springs 38 on each side, not one to a side as shown. When two springs 38 are used on each side, both are hooked to the eyes 33 and 36 and extend upwardly at an angle of approximately 35° apart. All of the helical tension springs on a side whether two or more are used are substantially in the same plane.

At the front of the seat frame and on each side thereof, a pair of coil springs 40 and 41 are provided. The inside ends of these springs engage the seat frame at eyes 33 and 36 respectively. The free end of each spring 40 engages an anchor plate 42 rigidly attached to the middle rail members 26 and 27 at intermediate points thereof. The free end of springs 41 engage front posts 9 and 10 respectively.

To resiliently support the legs of the user, a tiltable frame is provided on side 29 of the seat frame. This tiltable frame, also of heavy wire, comprises horizontal pieces 45 and 46 joined by horizontal sides 47 and 48 looped around wire 29.

and extending downwardly at 49 and 50. Coil springs 51 and 52 suitably anchored by fingers 53 to bottom rail 1 and extend to lower horizontal piece 46 tending to pull it forwardly and supply 5 the resiliency. This construction provides the spring edge of my invention which can act independently of the seat portion proper.

A heavy cloth seat 56 of canvas or jute webbing is resiliently supported by helical tension 10 springs 60 from sides 30, 31 and 32 of the seat frame and extends over cross piece 45 of the tiltable frame to bottom rail 1 where it is anchored in suitable fashion.

Suitable upholstery 61 may be provided over 15 the sides and back of the chair. A flap 62 of heavy or quilted fabric carried at the front of the chair by upholstery may be provided for covering the entire seat assembly and supporting springs. Thereafter a seat cushion, not shown, 20 may be disposed over flap 62.

It has been found that a spring suspension as described permits the seat to yield in all directions, both horizontal and vertical. With the 25 tilting frame at the front, there is a tendency for the entire spring suspension system to help a person get up out of the chair. When the weight of a user is shifted forward preparatory to rising, the rearward supporting springs having 30 been relieved from the weight, pull the seat upwardly. Also when the person rises so does the resilient seat, and so a person is truly assisted in getting out of this chair. This feature is not found in any kind of deep seated chair or 35 furniture. While sitting, a person may shift his weight and position against a resilient support in all directions.

Having described the invention, we claim:

1. A piece of furniture comprising four corner 40 posts, horizontal frame members joining adjacent posts near the bottom thereof, a back rest extending across the rear posts, arm rests extending between front and rear posts, a seat assembly comprising a horizontal frame, coil 45 springs extending from said arm rests to spaced points on said seat frame, a second frame extending forwardly from the front edge of said seat frame and movable up and down around said front edge as a pivot, means for resiliently 50 urging said second mentioned frame upwardly, and a flexible seat resiliently mounted on the rear and sides of the seat frame and extending over said second mentioned frame to the front horizontal frame member for limiting the upward movement of said second mentioned frame. 55

2. The piece of furniture of claim 1 wherein a fixed stop member is provided under each arm rest and above the seat frame for limiting the upward movement of the seat assembly.

3. A chair comprising four corner posts, horizontal frame members joining adjacent posts near the bottom thereof, a back rest extending across the rear posts, arm rests extending between front and rear posts, a seat assembly comprising a rectangular frame having sides below said arm rests, coil springs extending from said arm rests adjacent the ends thereof down to said seat frame sides, coil springs extending from spaced points of the rear side of said seat frame to the adjacent horizontal frame member, a second frame extending forwardly from the front edge of said rectangular frame and hinged thereto, means for resiliently urging said hinged frame upwardly, a flexible seat resiliently mounted on the rear and sides of said seat frame and extending over said hinged frame to the front horizontal frame member, and stop members carried by said chair frame below said arm rests and above the seat frame sides for limiting the upward motion of said seat assembly. 15

4. The chair of claim 3 wherein said seat frame is of heavy wire and wherein the hinged frame is of heavy wire bent into two rectangular planes with one extending forwardly of the seat and the other downwardly from the front edge of the seat frame with springs between the lower frame edge and front horizontal frame member forming the resilient urging means. 25

5. A chair comprising four spaced vertical posts formed as legs at the bottom, horizontal frame members joining adjacent posts near the bottom thereof, a back rest extending across the rear posts, arm rests extending between front and rear posts, a metal seat assembly comprising a 30 rectangular horizontal wire frame, coil springs extending from spaced points on each arm rest for supporting opposite frame sides, additional coil springs extending from the rear frame side to the rear horizontal frame member, coil springs 35 extending from the front posts to the front frame corners, a wire locked around the ends of the front of the wire frame and having one portion extending forwardly thereof and another portion extending downwardly thereof, coil springs 40 extending between the front horizontal frame member and the downwardly extending portion of the looped wire and tending to raise the forwardly extending portion, a seat portion of fabric and springs for supporting said fabric at the rear and sides of the horizontal frame, said fabric extending over said forwardly extending wire portion and being fastened to the front horizontal frame member. 45

6. The chair of claim 5 wherein a stop member is rigidly supported by said chair frame below each arm rest and above the wire frame side. 55
